UNITED STATES PATENT OFFICE.

FRANK W. SCHAFER, OF SIOUX CITY, IOWA, ASSIGNOR TO KELLOGG SWITCHBOARD & SUPPLY COMPANY, OF CHICAGO, ILLINOIS, A CORPORATION OF ILLINOIS.

AUTOMATIC TELEPHONE SYSTEM.

Application filed August 4, 1918. Serial No. 782,813.

To all whom it may concern:

Be it known that I, FRANK W. SCHAFER, a citizen of the United States of America, residing in Sioux City, county of Woodbury, 5 and State of Iowa, have invented certain new and useful Improvements in Automatic Telephone Systems, of which the following is a specification.

My invention relates more in general to 10 automatic telephone systems, but certain features thereof are not limited to automatic telephone systems but may be used in connection with other classes of telephone systems, and in other ways. One of the objects of my invention is to provide an improved and simplified automatic telephone system and another object is to provide improved trunk selecting apparatus. More particularly my improved trunk selecting apparatus looks to a structure in which a 15 trunk preselector is provided whereby an idle trunk line is always maintained in selective condition so that a simple circuit closure of the line in initiating a call will effect connection between the calling line and such an idle trunk by means of a related mechanism which I term a trunk connector. Other features of my invention will be more particularly referred to in the ensuing specification 20 and claims.

Referring now to the accompanying drawing in which all parts are shown at normal and in which like reference characters indicate like parts;

Fig. 1 comprising parts 1 and 2 illustrates the preferred circuit arrangement of an automatic telephone system embodying my invention;

Fig. 2 illustrates a trunk selecting mechanism or trunk switch, consisting of a common trunk-preselector AA and a plurality of associated trunk-connectors A;

Fig. 3 is a plan view of the trunk selecting mechanism showing more particularly the trunk connectors;

Fig. 4 illustrates a directive trunk selector switch, also known as a first or second selector switch; and

Fig. 5 illustrates diagrammatically a preferred trunking system.

Referring now more in general to the system shown in Fig. 1, the part 1 may be placed to the left part of part 2 and the circuit arrangement more readily followed.

For the purpose of simplifying the illustra-

tion I have shown only sufficient apparatus for a single connection between a calling substation B and a called substation C. The apparatus employed in such a connection consists preferably of a trunk switch comprising a trunk-preselector AA and a trunk-connector A, a first selector D which is a simple rotary switch, an intermediate or secondary trunk selecting mechanism comprising a trunk-preselector AA¹ and associated 60 trunk-connector A¹, and a connector switch E which may be of any type although I preferably employ a two-dimension switch and have illustrated the well-known Strowger connector. In connection with the called 65 substation C, I have shown only the associated trunk-connector A².

The substations may be of any suitable arrangement in which a calling device F is provided having primary contacts 1 and secondary contacts 2 so arranged that when the dial 3 is rotated and released, the contacts 1 are first closed a number of times according to the adjustment of the dial 3 and thereafter the secondary contacts 2 are closed a 70 single time. A ringing key RK is also provided as is also a secondary key SK. The hook-switch 4 is preferably arranged to momentarily close a ground connection to the secondary side S of the line when the receiver is removed and to ground both the primary side P and secondary side S when the receiver is replaced, providing the calling key CK is first operated to connect the 75 calling and releasing ground.

In general the operation of the system in completing a connection is as follows: Upon removal of the receiver at the calling substation B, ground connection is momentarily placed upon the secondary side of 80 the line, thereby momentarily energizing the selecting relay SL to cause the motor magnet MM to connect the wipers 6, 7, 8, to contacts 9, 10, 11 of the first idle trunk which has been preselected by the associated trunk-preselector AA, which trunk terminates in a 85 first selector switch D. As soon as a trunk is selected the test relay TR¹ of the associated preselector AA is energized and causes its motor magnet MM¹ to operate switch AA 90 so as to place the next idle trunk D in condition for connection to the next calling line of the group. The subscriber now by operating the dial F causes the primary relay PR to operate the motor magnet MM² and 95 100 105 110

thus advance the wipers 12, 13, 14 to select a set of contacts 15, 16, 17 according to the number of primary impulses transmitted from the contacts 1. After the transmission 5 of the primary impulses the secondary contacts 2 are closed a single time to cause the operation of the secondary relay SR and the switching magnet SW to move the side switch arms 18, 19 to their alternate position.

10 This secondary impulse remains for a sufficient period to cause the operation of intermediate trunk-connector A¹ to select an idle connector E.

15 The subscriber now operates the dial 3 to cause the operation of connector E by vertical relay VR and vertical magnet VM and the advancement of side switch arms 118, 119, 120, 121, to the second position.

20 The next movement of the dial F will cause the operation of vertical relay VR and rotary magnet ROM whereby the wipers 22, 23, 24 are extended to the terminals of the wanted line.

25 After the subscribers have finished their conversation they replace their receivers upon their respective switch-hooks, the replacing of the receiver at B effecting the energization of relays VR and ROR of connector E and thereby causing the energization

30 of the release magnet RM⁵, release relays RR³, RR² and RR in series to effect the restoration of the switches E, A¹, D and A.

Mechanism.

35 Now as to the mechanism which I preferably employ and referring to the automatic trunk switch of Figs. 2 and 3, I provide a plurality of trunk-connectors A and a common set of trunk contacts 9, 10, 11, and a common trunk-preselector AA. The pre-selector AA includes a stop 25 which may be moved into a plurality of positions corresponding to the trunk contacts 9, 10, 11, by

40 means of the motor magnet MM¹. The stop 25 is suitably carried by a sliding ratchet member 26 which is supported by the downwardly extending post 27, the ratchet 26 being so arranged that upon each energization

45 of the motor magnet MM¹ it receives one vertical step and is held in its advanced position by the retaining pawl 28. Release magnet RM¹ is also provided and so arranged

50 that when its armature 29 is attracted the pawl 28 and driving pawl 30 are moved free of ratchet 26 and held in this position by means of the locking arm 31. This arm 31 moves upwardly and locks the armature 29 in an attracted position until the ratchet 26

55 drops downwardly to normal and engages the pin 31¹ to move the catch 31 away from the armature 29 and allow it to retract. Any suitable automatic circuit breaker may be

60 provided for the motor magnet MM¹ and I have shown a well-known form of such a de-

vice comprising a pair of normally closed contacts 32, 33, contact 32 having a projection 32¹ and the contact 33 having an insulated member 34 so arranged that when the armature of MM¹ is attracted the laterally projecting member 35 engages the under side of projection 32¹ until member 35 passes beyond 32¹ where it engages the insulating member 34 and holds the contact 33 away from 32 thus interrupting the circuit for MM¹ and allowing the retraction of its armature, whereby the member 35 rides downwardly along the upper surface of 32¹ to maintain the contacts 32, 33 interrupted until the armature of MM¹ again reaches 70 normal. For each operation of MM¹ the wiper 36 advances one step along the contacts 37, the arrangement being such that the wiper 36 breaks contact with one terminal 37 before it engages the next contact. 75 When the switch AA is in its normal position the stop 25 places the lowermost or first set of contacts 9, 10, 11 in selective condition for an associated trunk-connector A. Wiper 75 and contact 76 are provided to effect the 80 automatic restoration of AA when it has traveled beyond its last contact set.

85 Trunk-connectors A, of which there are a plurality, and preferably twenty-five for each trunk switch, comprise a carriage 39 95 adapted to be moved up and down on the studs 40 said carriage 39 supporting a second movable device 41 which is adapted to move at right angles to the travel of the carriage 39. This device 41 carries a private 100 or busy wiper 8 and primary and secondary wipers 6 and 7 respectively. A downwardly projecting arm 42 is also carried by member 41 said arm 42 having a plurality of holding slots 43 adapted to co-operate with the corresponding holding arm 44 depending upon the contacts 9, 10, 11 connected with, as will be hereinafter more fully explained. There is such an arm 44 provided for each trunk-connector A. A pivoted stop member 45 is 110² also carried by the carriage 39 and has a pawl 46 which is adapted to engage the stop 25 when the carriage 39 is raised, the position of the engaging of stops 25 and 46 determining the set of contacts 9, 10, 11, which will be 115 connected with by the wipers 6, 7, 8.

120 The connecting operation of the wipers 6, 7, 8, is effected by the solenoid motor magnet MM which is adapted to attract its armature 47 whereby the arm 48 carrying the roller 49 moves said roller 49 upward against the inclined plane 50 which is carried by the member 40, this upward movement causing the carriage 39 to be moved vertically until the stops 25, 46 engage, whereby the continuing energization of MM and the continuing movement of roller 41 upon the plane 50 causes a right angular travel of the member 41 to move the wipers 6, 7, 8, into engagement with the set of contacts 9, 10, 11 130

corresponding to the adjustment of the stop 25. As the member 41 travels inward, the proper slot 43 moves into engagement with the corresponding arm 44 so as to guide the 5 wipers in their secondary travel and hold them even though magnet MM de-energizes. As the member 41 moves inwardly towards the contacts, the downwardly projecting arm 42 moves away from the portion 45¹ of the 10 pivoted arm 45 whereby spring 52 acts upon the end 45¹ and thus moves its pawl 46 clear of the stop 25 so that the stop 25 is free to be adjusted up or down. It will be understood that as soon as the wipers 6, 7, 8 engage 15 a set of contacts 9, 10, 11, the next corresponding preselector contact 37 is made busy to cause the advancement of stop 25 into its next idle selecting position as will be more clearly described in connection with the circuit arrangement illustrated.

As the secondary travel of the wipers 6, 7, 8 is completed, the lower end of the pivoted arm 53 allows an upward movement of the catch 54 and the movement of off-normal 25 contacts ON to their alternate position. This catch 54 also holds the wipers 6, 7, 8 in their connective position until the release magnet RM is energized to cause the arm 55 carried by armature 56 to engage the catch 30 54 and move it free of the arm 53 whereby the restoring spring 57 restores the member 41, thereafter the carriage 39 moving downwardly by gravity to its normal resting position.

35 I have illustrated two trunk connectors A, A and it is to be understood that a plurality of such trunk connectors A are common to each set of contacts 9, 10, 11. I preferably provide twenty-five units A for 40 each trunk switch.

Referring now to the first selector D, Fig. 4, it comprises a plurality of contact sets 15, 16, 17 and corresponding wipers 12, 13, 14, said contacts 15, 16, 17 being suitably insulated from each other as are also the 45 wipers 12, 13, 14. A motor magnet MM² is provided for advancing the wipers 12, 13, 14, along the contact sets 15, 16, 17 by means of a well-known form of ratchet and pawl 50 mechanism. A retaining pawl 58 is also provided for maintaining the wipers in an adjusted position, said pawl 58 being so arranged that when the release magnet RM² is energized, the release catch 59 carried by 55 the armature arm 60 hooks over the pin upon pawl 58 so that the retraction of the armature of RM² causes the withdrawal of pawl 58 to allow the restoration of the wipers. As the wipers reach normal, the arm 61 carried thereby engages the upper end of catch 60 59 moving it free of the pawl 58 and allowing said pawl 58 to again engage the wiper ratchet teeth.

Upon the first off-normal step of the 65 wipers of selector D, a stop 62 carried there-

by moves away from the pivoted arm 63 of the said switch arm 64 so that when the switching magnet SW is energized the said switch moves from its normal to its alternate position. The side switch is preferably provided with two-contact arms 18, 19 as shown in the circuit drawing, which arms normally rest upon contacts 65, 66 and in their alternate position upon contacts 67, 68. In the switch D of Fig. 4 and Fig. 1 part 1, I have used corresponding reference characters to indicate like parts.

Having described in general the mechanism and circuit arrangement employed, I will now briefly describe the preferred 70 trunking arrangement as shown in Fig. 5, in which I have shown the first and second hundred groups of a 1000 line system. I preferably arrange the lines in groups of 75 100, subdividing these groups into four sub-groups of 25 lines each and connect each such sub-group to a primary trunk switch A-AA, thus providing four primary trunk switches A-AA for each 100 lines. The contacts 9, 10, 11 of each four primary trunk 80 switches are multiply connected, there being 10 such contact sets and these extend to 10 first selectors D. While I preferably provide 10 trunks and 10 first selectors D for each 100 lines, it is to be understood the 90 number of contact sets and first selectors for each group of 100 lines may be varied according to the traffic requirements.

The first contact sets 15, 16, 17 of each 100 group of ten first selectors D extends to 10 trunk-connectors A¹ of a secondary trunk switch A¹-AA¹ in the first hundred group.

These trunk connectors A¹ of the first hundred group have access to 10 connectors E in the first 100 group as is indicated in the 105 drawing.

Referring again to the first selectors D, the second contact sets of each group of such switches D extend to the 10 secondary trunk-switches in the second hundred group, the third contact to 10 secondary trunk switches in the third hundred group, etc.

As the present arrangement is for a 1000 line system, the connectors of each 100 group should be accessible from the first selectors 110 D in each of the other hundreds groups and therefore for each group of 10 connectors I provide four secondary trunk switches A¹-AA¹ which four switches include 100 trunk-connectors A¹. As already described the 120 first 10 trunk-connectors A¹ are connected to the first contacts in the corresponding group of 10 first selectors D and I then connect the next 10 trunk-connectors A¹ to the 10 first selectors in the second hundred group. 125 This leaves 5 trunk-connectors A¹ on the first secondary trunk switch and therefore I connect these 5 together with the first five of the next secondary trunk switch to the first contact sets of the first selectors in the 130

third hundred group. The next 10 trunk-connectors A^1 are connected to the 10 first selectors in the fourth hundred group, and this method of connecting is extended from 5 the four secondary trunk switches A^1-AA^1 of each 100 group to the first selectors in the different hundreds group as will appear from the drawing.

Having described in general the arrangement of the system illustrated, I will now 10 describe more in detail the operation thereof in extending a connection between a calling and called substation.

Assuming that substation B desires to 15 extend a connection to called substation C whose number we will assume is 343, the subscriber at B first closes calling key CK and then removes his receiver from its switch-hook whereby ground is momentarily 20 connected to conductor S and through the winding of selecting relay SL and normal contact 70 to battery, causing the energization 25 of SL whereby its alternate contact 71 is closed causing the energization of the solenoid motor magnet MM. We will assume 30 that the preselector AA is in its normal position in which case the first selector D is idle and therefore the energization of MM moves the wipers 6, 7, 8, into engagement 35 with the first set of contacts 9, 10, 11 respectively thus extending the circuit of the calling line to first selector D shown. As the 40 trunk connector A is operated, contacts ON are moved to their alternate position whereby the contact 70 is interrupted to open the circuit of relay SL and the magnet MM, whereby both of these restore. The closing of alternate contact 72 of ON extends ground or busy potential to the test contacts 173 45 which, together with the contacts 175 and 174, appear at the connector switches having access to the line of substation B.

As soon as switch D is connected with, a 50 busy potential is placed upon its test contact 11 from ground through release RR, whereby a circuit is extended through said test contact 37, wiper 36, and test relay TR¹ to battery. Relay RR is of a low resistance while relay TR¹ is of a comparatively high 55 resistance so that RR does not energize but TR¹ does energize closing its alternate contact 73 and establishing an energizing circuit for the motor magnet MM¹. The armature of MM¹ is attracted and advances the wiper 60 36 one step into engagement with the next test contact 27. During this advance of the wiper 36, said wiper breaks connection with the contact on which it is resting before engaging the next contact and should relay 65 TR¹ interrupt its contact 73 during this travel of the wiper, the motor magnet circuit MM¹ is still maintained through its alternate contact 74 until the magnet MM¹ is fully energized at which time the contacts 32, 33 are interrupted causing a retraction of its

armature. If the said next engaged test contact 37 leads to a busy first selector D, there will of course, be a busy potential connected thereto through the relay RR of the associated trunk connector A and therefore relay 70 TR¹ would cause another operation of the motor magnet MM¹, such stepping operation of the preselector AA being continued until the wiper 36 reaches a contact 37 associated with an idle first selector D. Should all of 75 the contacts 37 have a busy potential connected thereto, the wiper 36 continues beyond the last contact 37 at which time the release wiper 75 engages the grounded contact 76 establishing an energizing circuit for the release magnet RM¹ and thereby causing the restoration of the preselector AA to normal, as already described in connection with the switch drawing Figs. 2 and 3. Such a selecting 80 operation of the trunk preselector AA is 85 continued until the wiper 36 engages an idle contact 37.

It is, of course, to be understood that sufficient trunking equipment is to be provided to take care of the traffic at the busiest period. 90

As a next step in extending the connection, the calling device F is operated to effect three closures of the primary contact springs 1 whereby ground is momentarily connected to the primary conductor P three times, 95 these three ground connections effecting three operations of primary relay PR over a circuit including said primary conductor P, wiper 6 and contact 9, arm 18 and normal contact 65 through the winding of PR to 100 battery. Responsive to the three operations of PR, alternate contact 77 is closed three times thereby causing three operations of motor magnet MM² whereby the wipers 12, 13, 14 of first selector D advance into 105 engagement with contacts 15, 16, 17, leading to a secondary trunk switch in the third hundred group.

After the transmission of the primary impulses, a single secondary impulse is transmitted by contacts 2 whereby ground is momentarily connected to the secondary conductor S through wiper 7 and contact 10, arm 19 and contact 66, and the winding of secondary relay SR to battery. Relay SR 110 therefore closes its alternate contact 78 causing the energization of the switching magnet SW whereby said switch arms 18, 19 are moved into their alternate position into connection with contacts 67, 68. 115

Although I have also shown a secondary key SK, I preferably arrange the calling device F so that the secondary impulse is of sufficient period to remain connected to the secondary conductor after the side switch 125 arms 18, 19 have operated, so that this secondary impulse will extend over wiper 13 and contact 16, selecting relay SL³ and ON³ to battery to cause the energization of SL³. This effects the closure of alternate contact 130

80 whereby the motor magnet MM^3 is energized and wipers $6^1, 7^1, 8^1$ are operated to effect connection with the first set of idle contacts $9^1, 10^1, 11^1$ which we will assume is 5 the first idle set of the group. Upon the operation of the trunk-connector A^1 of the secondary trunk switch, off-normal contact ON^3 is interrupted to cause the de-energization of SL^3 and MM^3 . Upon connection of wipers 10 $6^1, 7^1, 8^1$, with contacts $9^1, 10^1, 11^1$ respectively, a busy potential is placed upon the test contact 11^1 traced from ground through RR of trunk-connector A , contacts $8, 11$, the low resistance winding of RR^2 , contacts 14 15 and 17 , low resistance relay RR^3 , contacts 8^1 and 11^1 , contact 37^1 and the wiper 36^1 through the winding of high resistance test relay TR^4 to battery. The current in this circuit is sufficient to cause the energization 20 of TR^4 but not of the release relays RR , RR^2 and RR^3 . The energization of TR^4 causes the operation of the trunk-preselector AA^1 in a manner as described in connection with AA .

25 Connection has now been extended from the calling substation to an idle connector E in the third hundred group of lines, which group includes the line of substation 343. The subscriber now operates calling device F 30 to transmit four impulses through primary conductor P through the winding of the vertical relay VR to battery. Relay VR therefore is operated four times effecting four closures of its alternate contact 81 whereby 35 four impulses are transmitted through the vertical magnet VM traced from ground at said alternate contact 81 , normal contact 86 , side switch arm 118 and its normal contact through the winding of VM to battery. The 40 vertical magnet VM is therefore operated to step the wipers $22, 23, 24$ opposite the fourth row of contacts $82, 83, 84$ which now includes the terminals of substation 343.

45 After the transmission of the four primary impulses, a single secondary impulse is transmitted over the secondary conductor S and through the rotary relay ROR of connector E to battery. Relay ROR is operated a single time to close its alternate 50 contact 87 whereby a circuit is closed through private magnet PV and side switch arms $118, 119, 120$ and 121 are moved to their intermediate position in a well-known manner.

55 The subscriber at B now operates the calling device F to transmit three primary impulses over the primary conductor P and through the vertical relay VR to battery whereby three primary impulses are transmitted through the rotary magnet ROM traced from ground at said alternate contact 81 , normal contact 86 , said switch arm 118 and its middle contact, through the winding of ROM to battery. Magnet ROM 60 therefore operates wipers $22, 23, 24$ to en-

gage the third set of contacts $82, 83, 84$, which are the terminals of the line of substation 343.

After the transmission of the three last primary impulses, a secondary impulse is 70 again transmitted over the secondary conductor S and through the winding of rotary relay ROR to battery. A circuit for private magnet PV is thus again established from ground at alternate contact 87 and through 75 the winding of PV to battery causing its energization and the movement of side switch arms $118, 119, 120$ and 121 to their third position, that is, if the wanted line is idle, which we will assume it is. 80

The connection having been completed between the calling and called lines, the subscriber at substation D depresses the ringing key RK whereby ground is connected to the primary conductor and through the vertical relay VR to battery, causing its energization. Alternate contact 81 of VR is therefore closed establishing an energizing circuit for ringing relay RI through the side switch arm 118 in its third contact position, 90 whereby said relay RI is energized to connect the ringing generator G in bridge of the terminals of the called line and to effect the operation of the call bell at substation C . 95

The subscriber at substation C in response to the call, removes his receiver from its switch-hook thereby completing the conversational circuit which is traced over the heavily marked conductors, talking battery 100 being supplied from the substations B and C .

Releasing.

After the subscribers have finished their conversation they replace their receivers 105 upon their respective switch-hooks thereby momentarily grounding both sides of the line, but in the case of the called substation this has no effect upon the release. At the calling substation though, this grounding 110 of the two sides of the line extends ground connection over the primary and secondary talking conductors and through the vertical and rotary relays of the connector E to battery causing their energization. Contacts 115 $89, 90$ are thus closed establishing a release circuit for the different switches, traced from battery through the winding of release magnet RM^5 , contacts $89, 90$, conductor 91 , contact 11^1 , and wiper 8^1 , release relay RR^3 , 120 contact 17 and wiper 14 , release relay RR^2 , contact 11 and wiper 8 , and the winding of release relay RR to ground. The energization of RM^5 is effective to restore connector switch E to normal in a well-known 125 manner and the energization of RR^3 closes a circuit through release magnet RM^3 of the secondary trunk connector A^1 , and upon the interruption of the circuit for RM^3 and its ensuing de-energization, the latch 54 is 130

released from the arm 53 thus allowing the restoration of the wipers 6¹, 7¹, 8¹.

Upon energization of RR² of first selector D, circuit is closed through its release magnet RM² which attracts its armature and upon de-energization withdraws the retaining pawl 58, shown in Fig. 4, allowing restoration of wipers 12, 13, 14.

Upon energization of RR of primary 10 trunk-connector A, circuit is closed through release magnet RM which is energized and de-energized, allowing restoration of the wipers 6, 7, 8, to normal.

The restoration of switch A to normal 15 removes the busy potential from the connector test terminal 178 thereby placing the line of substation B in an idle condition once more. The disconnection of wiper 8 from contact 11 also removes the busy potential 20 from the corresponding first selector D whereby it is again in selectable condition by any of the four associated preselectors AA or one hundred trunk-connectors A.

The removal of busy potential from the 25 test contact 17 of first selector D and thus also from wiper 8¹ and associated test contact 11¹ of trunk connector A¹, places the connector E in a selectable condition.

30 *Called line busy.*

In the connection previously described it was assumed that the called line was idle at the time connection was made therewith, and I will now describe the operation of the 35 system when the connector E connects with the terminals of a busy line. In such case the operation is the same as that previously described up to the transmission of the last impulse, at which time assuming the line 343 is busy and its test contact 84 has a ground or 40 busy potential connected thereto, when the private magnet PV is energized responsive to the last secondary impulse, a circuit is traced from said grounded test contact 84 45 through wiper 24, side switch arm 121 and its middle contact, alternate contact 88, and the winding of RM⁵ to battery, causing the energization of RM⁵ and the release of connector E. The calling subscriber of course, 50 up to this time is not aware of the busy condition of the called line and therefore operates the ringing key RK in the usual manner thus operating vertical relay VR and thereby the vertical magnet VM, stepping the 55 switch E off-normal and closing the vertical off-normal contact VON. A characteristic busy signal from busy back BB is therefore connected to the talking conductors and the calling subscriber, hearing this signal, is 60 aware that the called substation is busy and replaces the receiver upon its switch-hook grounding both the conductors S and P. The grounding of these conductors of course operates relays VR and ROR, whereby the 65 release relays and release magnets of the

switches used in establishing connection are operated in a manner as previously described.

Although I have chosen to illustrate my invention in a 1000 line automatic telephone 70 system, it is to be understood that the capacity of my invention is by no means limited to 1000 lines, as other directly controlled selectors as D and associated automatic trunk switches A-AA may be provided between the secondary trunk switch and connector E. Or the connectors E may be connected directly to the terminals 9, 10, 11 of the primary trunk switch. It will also be apparent that many changes and modifications in the circuit arrangement and apparatus construction may be made, and therefore I do not desire to be limited to the particular matter shown and described but aim to cover all that which comes within the 85 spirit and scope of the appended claims.

What I claim as new and desire to secure by United States Letters Patent is:

1. A trunk switch for telephone systems comprising a plurality of trunk connectors, 90 trunk lines common to said trunk connectors, a set of contacts for each trunk common to the connectors, a trunk preselector common to said trunk connectors for automatically maintaining the contact set of an idle one of 95 said trunks in connective condition, a selecting relay for each of said trunk connectors, and a motor magnet and mechanism controlled thereby responsive to said selecting relay for operating the associated trunk connector to connect with the contact set of that trunk which is in connective condition. 100

2. A trunk switch for telephone systems comprising a plurality of trunk connectors, 105 trunk lines common to said trunk connectors, a single set of terminals for each of said trunk lines appearing before said trunk connectors, a trunk preselector having terminals multiply connected to said trunk line terminals, automatic means for operating 110 said preselector to maintain the contact set of an idle one of said trunks in connective condition including said multiple terminals, and means included in each of said trunk connectors for operating the associated trunk 115 connector to connect with the contact set of that trunk which is in connective condition.

3. A trunk switch for telephone systems comprising a plurality of trunk connectors, 120 trunk lines common to said trunk connectors, a single set of terminals for each of said trunk lines appearing before said trunk connectors, a trunk preselector having terminals multiply connected to said trunk line terminals, automatic means for operating 125 said preselector to maintain the contact set of an idle one of said trunks in connective condition including said multiple terminals, a selecting relay for each of said trunk connectors, and a motor magnet and mechanism controlled 130

- thereby responsive to said selecting relay for operating the associated trunk connector to connect with the contact set of that trunk which is in connective condition.
- 5 4. A telephone exchange system comprising telephone lines, individual trunk-connectors for said lines, trunk lines common to said trunk-connectors, a set of contacts for each trunk common to the connectors, a 70 trunk-preselector common to said trunk-connectors for maintaining the contact set of an idle one of said trunks in connective condition, and means included in each of said trunk connectors effective upon initiation 75 of a call over the associated line to cause the associated trunk-connector to connect with the contact set of that trunk which is in connective condition.
5. A telephone exchange system comprising 80 telephone lines, individual trunk-connectors for said lines, trunk lines common to said trunk-connectors, a set of contacts for each trunk common to the connectors, a trunk-preselector common to said trunk-connectors for automatically maintaining the contact set of an idle one of said trunks in connective condition, a line or selecting relay for each of said trunk-connectors energized responsive to a call over the associated line, 85 and a motor magnet responsive to said selecting relay and mechanism controlled thereby for operating the associated trunk connector to connect with the contact set of that trunk which is in connective condition.
- 30 6. A telephone exchange system comprising 90 telephone lines, individual trunk connectors for said lines, trunk lines common to said trunk connectors, a single set of terminals for each of said trunk lines appearing before said trunk connectors, a trunk preselector having terminals multiply connected to said trunk line terminals, automatic means for operating said preselector to maintain the contact set of an idle one of 95 said trunks in connective condition including said multiple terminals, and means included in each of said trunk connectors effective upon initiation of a call over the associated line to cause the associated trunk connector to connect with the contact set of that trunk which is in connective condition.
- 50 7. A telephone exchange system comprising 100 telephone lines, individual trunk connectors for said lines, trunk lines common to said trunk connectors, a single set of terminals for each of said trunk lines appearing before said trunk connectors, a trunk preselector having terminals multiply connected to said trunk line terminals, automatic means for operating said preselector to maintain the contact set of an idle one of 105 said trunks in connective condition, said automatic means including said multiple terminals, a line or selecting relay for each 110 of said trunk connectors energized responsive to a call for the associated line, and a motor magnet and mechanism controlled thereby responsive to said selecting relay for operating the associated trunk connector to connect with the contact set of that trunk which is in connective condition.
12. A telephone system comprising telephone lines, first selectors and connectors, automatic switching devices for interconnecting said lines and first selectors, calling devices at the substations of said lines for operating the first selectors and connectors, and interposed non-directive automatic switching devices also responsive to said calling devices for interconnecting said first 130 selectors and connectors, each of said selectors being provided with a number of said non-directive automatic switching devices for its individual use.
9. A telephone system comprising telephone lines, first selectors and connectors, calling devices at the substations of said lines for operating the first selectors and connectors, automatic switching devices irresponsible to said calling devices for interconnecting said lines and first selectors, interposed non-directive automatic switching devices responsive to said calling devices when operating said first selectors, for interconnecting said first selectors and connectors, ringing means for said connectors, and a ringing key at the calling substation for operating said ringing means to connect ringing current to the called substation each time said key is operated.
10. A telephone system comprising telephone lines, first selectors and connectors, calling devices at the substations of said lines adapted for transmitting primary and secondary impulses for operating the first 105 selectors and connectors, automatic switching devices irresponsible to said calling devices for interconnecting said lines and first selectors, interposed non-directive automatic switching devices responsive to a secondary 110 impulse from said calling devices when operating said first selectors, for interconnecting said first selectors and connectors, audible busy-back signaling means for said connectors, and means for automatically restoring said connectors when said connectors are connected to busy lines to connect said busy-back signaling means in circuit with the calling lines.
11. A trunk switch for telephone systems 120 comprising a plurality of trunk connector switches, wipers and motor magnets for each of said connectors, and mechanism controlled by said motor magnets for operating said trunk connectors independently for connecting to a common set of trunk contacts.
12. A trunk switch for telephone systems comprising a plurality of trunk connectors, sets of contacts common to said connectors, a preselector having operating positions cor- 130

- responding to said sets of contacts, means whereby said preselector may be operated to place one of said contact sets in connective condition, and mechanism for said 5 trunk connectors whereby said trunk connectors may be operated to connect with the contact set in connective condition.
13. A trunk switch comprising a plurality of individual selectors each having contact makers and driving mechanism therefor, and a set of contacts common to said contact makers.
14. A trunk switch comprising a plurality of individual selectors each having contact makers and driving mechanism therefor, a set of contacts common to said contact makers, and means whereby any selector may seize said contacts to the exclusion of the other selectors.
15. A trunk switch comprising a plurality of individual selectors each having contact makers and driving mechanism therefor, sets of contacts common to said contact makers, and means whereby any driving mechanism 25 is controlled for operating its contact makers to connect with any of said contact sets.
16. A trunk switch comprising a plurality of individual selectors each having contact makers and driving mechanism therefor, sets 30 of contacts common to said contact makers, means whereby any driving mechanism is controlled for operating its contact makers to connect with any of said contact sets and means to prevent any other selector from 35 seizing a contact set already connected with.
17. A trunk switch comprising a plurality of individual selectors each having contact makers and driving mechanism therefor, sets of contacts common to said contact makers, 40 stop mechanism having stop positions for the selectors corresponding to the contact sets, and means for operating said stop mechanism.
18. A trunk switch comprising a plurality of individual selectors each having contact makers and driving mechanism therefor, sets 45 of contacts common to said contact makers, stop mechanism having stop positions for the selectors corresponding to the contact sets, and means for advancing said stop mechanism each time a contact set is seized.
19. A trunk switch comprising a plurality of individual selectors each having contact makers and driving mechanism therefor, sets 55 of contacts common to said contact makers, trunk lines leading from said contact sets, a preselector for maintaining the contact set of an idle trunk in connective condition, and means whereby when a selector seizes said 60 idle contact set said preselector is advanced to maintain the contact set of the next idle trunk in selectable condition.
20. A trunk switch comprising a plurality of individual selectors each having contact 65 makers resting in their normal position, contact sets for said contact makers, conductors leading from each contact set, driving mechanism for each selector for moving its associated contact makers to any one of said sets of contacts, a preselector for maintaining an 70 idle trunk in connective condition, and means for operating any of said driving mechanisms to advance their contact makers from their normal position into engagement with the preselected contact set. 75
21. A telephone system comprising telephone lines, a selector individual to each line provided with contact makers, sets of contacts adapted to be engaged by the contact makers of any of said selectors, trunk 80 lines leading from said contacts, driving mechanism for each selector for moving its associated contact makers to any one of said sets of contacts, and a preselector normally maintaining the contact set of an idle trunk 85 in connective condition.
22. A telephone system comprising telephone lines, a selector individual to each line provided with contact makers, sets of contacts for said contact makers, trunk lines 90 leading from said contact sets, driving mechanism for each selector for moving its associated contact makers to any one of said contact sets, a preselector maintaining the contact set of an idle trunk in connective condition, and means for operating the driving mechanism of any of said selectors to advance their contact makers from their normal position to connect with the preselected contact set and means for operating any of 95 the driving mechanisms. 100
23. A telephone system comprising telephone lines, first selectors and connectors, automatic switching devices individual to the lines for interconnecting said lines and 105 said first selectors, calling devices at the substations of said lines for operating the first selectors and connectors, interposed non-directive automatic switching devices provided with individual active contacts, and motor 110 mechanism for said last devices for moving said active contacts to thereby interconnect said first selectors and connectors, said connectors comprising a part of the talking circuit of said telephone system. 115
24. A telephone system comprising telephone lines, first selectors and connectors, automatic switching devices for interconnecting said lines and said first selectors, calling devices at the substations of said 120 lines for operating the first selectors and connectors, interposed progressively movable non-directive automatic devices provided with active contacts, each of said last devices being for the individual use of a particular selector, and motor mechanism for said non-directive devices for moving said contacts into connection with preselected connectors, said connectors comprising a part of the talking circuit of said telephone system. 125 130

25. A telephone system comprising telephone lines, first selectors and connectors, automatic means for interconnecting said lines and first selectors, interposed progressively movable non-directive automatic switching devices provided with movable wipers for interconnecting said first selectors and connectors, each of said first selectors being provided with one of said non-directive devices for its exclusive use, and a common mechanism for preselecting the connectors that the selectors connect with. 70
26. A telephone system comprising telephone lines, first selectors and connectors, automatic switching devices for interconnecting said lines and first selectors, calling devices at the substation of said lines for operating said selectors and connectors, interposed non-directive automatic switching devices also responsive to said calling devices for interconnecting said selectors and connectors, each of said selectors being provided with a plurality of said non-directive devices for its exclusive use, and common mechanism for selecting the connectors for said non-directive switching devices. 80
27. A telephone system comprising telephone lines, a first selector and a plurality of connectors, automatic switches for pre-selecting said first selectors and said connectors, automatic means for connecting one of said lines to said first selector, interposed progressively movable non-directive automatic switching devices provided with movable contacts, and motor mechanism for said non-directive switching devices for moving said contacts, thereby connecting said selector to one of said connectors. 85
28. A telephone system comprising telephone lines, a first selector and a plurality of connectors, switching means for connecting a calling one of said lines to said first selector, interposed non-directive progressively movable automatic switching devices provided with active contacts, each of said non-directive devices being for the exclusive use of a particular selector, stationary contacts for said connectors, motor mechanism for moving said active contacts into connection with an idle one of said connectors, and common mechanism for selecting the connected with connector. 90
29. A telephone system comprising telephone lines, first selectors and connectors, automatic switching devices for connecting said lines and first selectors, calling devices at the substations of said lines for operating said first selectors and connectors, and interposed non-directive automatic switching devices individual to each of said selectors for connecting said selectors to said connectors. 105
30. A telephone system comprising telephone lines, a first selector and a plurality of connectors, an automatic switching device for connecting said first selector to a calling one of said lines, and interposed non-directive progressively movable automatic connecting devices individual to said selector for connecting said selector to one of said connectors. 110
31. A telephone system comprising telephone lines, a first selector and a plurality of connectors, an automatic switching device for connecting said first selector to a calling one of said lines, interposed automatic switching devices individual to said selector for connecting said selector to said connectors, and common mechanism for selecting connectors. 125
32. A telephone system comprising telephone lines, a first selector and a plurality of connectors, an automatic switching device for connecting said first selector to a calling one of said lines, and interposed automatic switching devices for the exclusive use of said selector for connecting said selector to said connectors. 130
33. A telephone system comprising telephone lines, a first selector and connectors, an automatic switching device for connecting a calling one of said lines to said selector, calling devices at the substation of said lines for operating said first selector and connectors, interposed automatic switching devices individual to said first selector for connecting said first selector to said connectors. 135
34. A telephone system comprising telephone lines, a first selector and connectors, automatic switching devices for connecting a calling one of said lines to said selector, calling devices at the substation of said lines for operating said first selector and connectors, interposed automatic switching devices individual to said first selector for connecting said first selector to said connectors, and common mechanism for pre-selecting connectors. 140
35. A telephone system comprising telephone lines, a first selector and connectors, an automatic switching device for connecting a calling one of said lines to said selector, calling devices at the substation of said lines for operating said first selector and connectors, interposed non-directive progressively movable automatic switching devices for the exclusive use of said first selector for connecting said first selector to said connectors. 145
36. A telephone system comprising telephone lines, a selector switch and a plurality of connectors, means for connecting a calling one of said lines to said selector switch, a calling device at the substation of said calling line for directly controlling said selector, a plurality of non-directive automatic switching devices individual and accessible to said selector, and means for operating one of said non-directive switching devices. 150

devices for connecting with one of said connectors.

37. A telephone system comprising telephone lines, a selector switch and a plurality of connectors, means for connecting a calling one of said lines to said selector switch, a calling device at the substation of said calling line for directly controlling said selector, a plurality of non-directive automatic switching devices individual and accessible to said selector, means for operating one of said non-directive switching devices for connecting with one of said connectors, and means for preselecting connectors.

38. A telephone system comprising telephone lines, a first selector and a plurality of connectors, automatic means for connecting said first selector to a calling one of said lines, and an interposed non-directive progressively movable switching device for the exclusive use of said selector for connecting said selector to one of said connectors.

39. A telephone system comprising calling and called telephone lines, first selectors and connectors, automatic switching devices individual to the lines for interconnecting said lines and said first selectors, calling devices including dials at the substations of said lines for operating the first selectors and connectors, said automatic switching devices operative independently of said dials, interposed non-directive automatic switching devices provided with motor mechanism for interconnecting said first selectors and preselected connectors, audible busy-back means for said connectors, and means for automatically restoring said connectors when connected to busy called lines to connect said busy-back means in circuit with the calling lines.

40. In a telephone system, a series of non-numerical switches, a second series of numerical switches to which said first series

is adapted to extend a connection, and a 45 third series of switches to which said second series is adapted to extend a connection, each switch of said second series having a plurality of switches on said third series which are individual to each of said second series 50 of switches.

41. In a telephone system, a series of non-numerical switches, a second series of numerical switches to which said first series is adapted to extend a connection, and a 55 third series of switches divided into groups to which said second series is adapted to extend a connection, each switch of said second series having an individual switch in each group of said third series of switches. 60

42. In a telephone system, a plurality of lines, a numerical switch for electing one of said lines, a non-numerical preselecting switch associated with each of said lines, other lines, means for operating said non-numerical switch to connect with one of said other lines, said numerical and non-numerical switches having selective movement in a single plane.

43. In a telephone system, a plurality of 70 lines, a numerical switch for electing one of said lines, a non-numerical preselecting switch associated with each of said lines, other lines, means for operating said non-numerical switch to connect with one of said 75 other lines, said numerical switch having rotary motion in selecting one of said first lines, and a solenoid motor magnet for said non-numerical switch for moving the same in a single plane to connect with one of said 80 other lines.

Signed by me at Sioux City, county of Woodbury, and State of Iowa, in the presence of two witnesses.

FRANK W. SCHARF.

Witnesses:

MAX McGAN,
L. BRIDWELL.
